UNITED STATES PATENT OFFICE.

HARRY GILLIAM, OF SPRINGFIELD, OHIO.

INCUBATOR.

1,059,605.

Specification of Letters Patent.

Patented Apr. 22, 1913.

Application filed October 10, 1911. Serial No. 653,796.

To all whom it may concern:

Be it known that I, HARRY GILLIAM, a citizen of the United States, residing at Springfield, in the county of Clark and State 5 of Ohio, have invented new and useful Improvements in Incubators, of which the following is a specification.

This invention relates to incubators and the object of the invention is to provide a 10 simple and efficient device of this character which is constructed to operate without a fire and at the same time to maintain a substantially even temperature throughout the hatching period.

15 A further object of the invention is the provision of a device of this character wherein the tray support is supported directly by the tank or heating element so that the heating element and tray support 20 may be removed from the casing as a unit and where the tray drawer may be removed independently of the tray support.

25 Further objects of the invention will appear as the following specific description is read in connection with the accompanying drawing which forms a part of this application, and in which:—

30 Figure 1 is a perspective view of the device. Fig. 2 is a longitudinal section therethrough. Fig. 3 is a transverse section. Fig. 4 is a perspective view of the tray drawer removed. Fig. 5 is a similar view of the tray. Fig. 6 is a perspective view of the heating element and tray drawer sup- 35 port removed from the casing.

Referring more particularly to the drawing, 1 represents a casing which is supported upon legs 2 and is provided with a removable top 3 which is secured to or otherwise 40 connected to the casing and has a port or opening 4 therein for a purpose which will hereinafter be described. The end 5 of the casing is provided with a sight glass 6 and the end 7 of the casing is provided with an 45 opening 7' through which the tray supporting drawer 8 is adapted to pass. Secured in each corner of the casing are reinforcing uprights 9 having supporting shoulders 10 formed therein upon which rests the hot 50 water tank 11. This tank has a plurality of substantially U-shaped pipes 12 connected to the bottom adjacent the side edges thereof and extending beneath a drawer supporting frame which consists of a side member 13 and a bottom member 14. The said members 55 are notched as shown at 15 to receive

the pipes 12 and project slightly beyond the bottom which rests directly upon the pipes as shown. The frame is somewhat narrower than the tank so that the side pieces 60 will lie inside of the pipes 12 so as to provide a space 16 which is filled with any suitable heat insulating material such as mineral wool or the like. This space extends the full depth of the casing on the sides thereof and 65 the depth of the tank on the ends thereof, the insulation being lifted out in front of the sight glass at the opening 7'. The space also extends over the top of the tank, between the same and the top of the casing. 70

Projecting vertically from one end of the tank and passing through the opening 4 in the top is a supply pipe 17 which is provided with a valve 18 and with a funnel 19. Adjacent the opposite corner of the tank, an 75 outlet nipple 20 is secured to the tank and passes through an aperture 21 in the casing and is provided with a valve 22 to control the discharge of the liquid from the tank.

A suitable tray receiving drawer 23 is 80 slidably mounted in the casing and rests upon the bottom 14 of the supporting frame and is provided with a sight glass 24 in its front end so that the contents of the tray 25 may be properly inspected from the front 85 end of the machine. When the drawer and this tray are removed from the casing and frame and the top 3 is removed from the casing, the tank and this supporting frame may be removed from the casing as a unit. 90

The bottom 26 of the casing 1 is provided with a plurality of vent holes 27 which are covered by shields 28 and the bottom 14 of the frame is also provided with vent holes 28 so that the eggs may be properly venti- 95 lated during incubation.

In the operation of this device a sufficient quantity of water to fill the tank is brought to the boiling point and placed in the tank so as to heat the same and radiate the heat 100 thereof over the eggs. This heat from the hot water will last approximately twelve hours when it is renewed by withdrawing a small portion of the water and again heating it to the boiling point and inserting it 105 in the tank with the partially cool water. It has been found by actual demonstration that this method of incubation is much more satisfactory than that of a thermostat regulator. At the latter part of each heating 110 period, the water in the tank has its temperature sufficiently reduced to properly cool

the eggs so that they will never become over-heated and thus ruin the hatch.

Having thus fully described the invention, what I claim as new, is:—

- 5 In an incubator, a casing, a hot water tank removably mounted therein, radiating pipes depending from the tank, a drawer supporting frame carried by said pipes and comprising side and bottom members, said side
- 10 members being provided with notches to receive and hold the pipes in spaced relation,

and a tray supporting drawer mounted in the frame and projecting through the casing, said drawer locking the tank against removal when in position in the frame.

15

In testimony whereof I affix my signature in presence of two witnesses.

HARRY GILLIAM.
